HAIR DRYER NOZZLE

Frank E. Gonzales, 7842 Santa Monica Ave.,
Stanton, Calif. 90680

Filed Jan. 30, 1975, Ser. No. 545,364

Term of patent 14 years

Int. Cl. D28—03

U.S. Cl. D86—10 F

FIG. 1 is a perspective view taken from below and at the discharge end of a hair dryer nozzle showing my new design;

FIG. 2 is a top plan view of the nozzle;

FIG. 3 is an end elevational view of the nozzle taken from the discharge end;

FIG. 4 is a side elevational view of the nozzle;

FIG. 5 is an end elevational view of the nozzle taken from the opposite end from that of FIG. 3; and

FIG. 6 is a longitudinal sectional view of the nozzle taken along line 6—6 of FIG. 3.

I claim:

The ornamental design for a hair dryer nozzle, as shown.
